AUGUST KAPPENBERG, OF BAYSIDE, NEW YORK, N. Y., ASSIGNOR, BY MESNE ASSIGNMENTS, TO AUTOMATIC LIGHTER CORPORATION, OF STAMFORD, CONNECTICUT, A CORPORATION OF DELAWARE

CIGARETTE DISPENSING AND LIGHTING CONTAINER

Application filed October 20, 1925. Serial No. 63,628.

This invention has relation to smokers' articles or accessories, and has particular reference to a cigarette or cigar dispensing and lighting container which is especially designed as an accessory to motor vehicles.

One of the outstanding objects of the present invention is to provide a container for cigarettes, cigars, or the like, adapted to be installed upon the instrument board of a motor vehicle to contain a supply of cigarettes or cigars, and equipped with means for singly dispensing lighted cigarettes or cigars with a minimum of effort on the part of the driver of a vehicle, whereby detraction of his attention from the steering and controlling of the vehicle for the purpose, is avoided.

More specifically the invention comprehends a cigarette dispensing and lighting container which includes a container body having a stacked supply of cigarettes together with means at the lower end of said body for isolating the lowermost cigarette, and means operated by the isolating operation for simultaneously creating a suction through the cigarette from one end and for igniting the opposite end to effectually light the cigarette, after which the same may be readily removed for smoking.

The invention furthermore contemplates a device of the character described which is comparatively simple in its construction and mode of use, inexpensive to manufacture and install, and which is highly efficient in its purpose.

With the above recited and other objects in view, reference is had to the following specification and accompanying drawings in which there is exhibited one example or embodiment of the invention which is in no way intended as a limitation upon the scope of the appended claims as it is to be clearly understood that variations and modifications which properly fall within the scope of said claims may be resorted to when found expedient.

In the drawings—

Figure 1 is a front view of the dispensing and lighting container;

Fig. 2 is a vertical sectional view there-

through taken approximately on the line 2—2 of Fig. 1;

Fig. 3 is a similar view taken approximately on the line 3—3 of Fig. 1;

Fig. 4 is an enlarged fragmentary sectional view through the lower end of the container, illustrating the position of parts prior to the isolation and lighting of the cigarette;

Fig. 5 is a similar view illustrating the 60 cigarette isolated and being lighted;

Fig. 6 is a fragmentary horizontal sectional view taken approximately on the line 6—6 of Fig. 4;

Fig. 7 is a sectional view through the 65 switch taken approximately on the line 7—7; of Fig. 4;

Referring to the drawings by characters of reference, 10 designates a substantially rectangular container body closed by a substantially semi-cylindrical closure 11 at its lower end, which is hinged thereby by a spring hinge 12, which normally disposes the closure in closed relation to the body. The upper end of the body is open and is 75 adapted to receive therein a supply of cigarettes, cigars, or the like, in stacked relation, as indicated in Figs. 4 and 5.

In order to provide means for singly dispensing the cigarettes, a cylindrical member 80 13 is mounted in the lower end of the body 10 for rotatory movement, said member having its opposite ends 14 and 15 projecting through the side walls 16 of the body. That portion of the member 13 disposed between 85 the inner sides of the side wall is cut away to approximately one-half of its circumference, as at 17, to provide a receiving opening for the lowermost cigarette C of the stack and permitting said lowermost cigarette 90 when the opening is disposed uppermost to drop through and into the member 13. The end 15 of the member 13 extends into a non-rotary outwardly projecting, cylindrical casting 18 which is closed at its outer end by 95 an axially apertured head 19. A tubular sleeve 20 is mounted within the end 15 for relative axial sliding movement with respect to said end and for turning movement therewith through the medium of a transverse 100

pin 21, which extends through a longitudinal slot 22 in the end 15. The outer extremity 23 of the pin projects into a circumferential groove 24 in the casing 18, which groove is of a length substantially equal to one-half of the circumference of the casing 18 and of a width approximately equal to the length of the slot 22 in the end 15, whereby the member 13 and the sleeve are limited 10 to approximately one-half a revolution. The sleeve 20 is provided with an outwardly projecting stem 25 extending through the axial opening in the head 19 of the casing 18, and said stem is provided at its outer end with a radially projecting handle 26 secured to the stem. A coiled spring 27 is interposed between a bearing washer 28 on the outer end of the head 19 and the manipulating handle 26 and the opposite terminals 20 29 and 30 are respectively embedded and anchored in the handle 26 and the head 19 so that said spring functions to normally slide the sleeve axially outward to engage its outer end with the head 19, and, at the 25 same time, to turn the handle, stem, sleeve 20 and member 13, in a clockwise direction to dispose the opening or cutaway portion 17 upwardly. The inner end of the sleeve is flared outwardly as at 31, and under the 30 action of the spring 27 is normally disposed flush with the inner surface of the right wall 16 as illustrated in Fig. 4. The casing 18 is provided with a radial opening 32 in which is threadedly engaged the nipple 33 35 of a suction tube 34 leading to a suction-creating means, such as the vacuum tank of a motor car, the intake manifold, or the like.

The end 15 of the member 13 is provided 40 with a radial port 35 disposed in circumferential alignment with the opening 32 and normally out of register therewith when the member 13 is in its normal position illustrated in Figs. 4 and 6. The sleeve 20 is 45 provided with a radial port 36 which is normally out of register with the port 35 when the sleeve is urged axially outward by the spring 27, as illustrated in Figs. 4 and 6, but which is capable of being disposed in register with the port 35 by inward sliding movement of the sleeve with respect to the end 15. The ports 35 and 36 when thus registered are adapted to aline with the opening 32 when the handle 26 is manipulated to 55 turn the sleeve and member 13 against the action of the spring 27 to the position illustrated in Fig. 5.

The opposite end 14 of the member 13 has mounted therein an insulated block 37, on 60 the inner face of which is arranged a resistance coil 38 constituting an electric heating element. The central terminal of the coil is connected with an outwardly projecting contact pin 39 while the outer terminal 65 is connected with an outwardly projecting

contact pin 40. A stationary cylindrical housing 41 is connected to and projects outwardly from the left side wall of the body 10 and receives the end 14 of the member 13. The outer end of the housing 41 has 70 mounted thereon a stationary insulated block 42 provided with a sleeve-like central socket 43 connected with a conductor 44 at its outer end and frictionally receiving the central contact pin 39. A radially spaced conductor 75 sleeve 45 connected with a conductor wire 46 extends, through the block 42 and has connected with its inner end an arcuate contact plate 47 with which the contact pin 40 is engageable and disengageable by the relative turning movement of the member 13 and block 37 with respect to the housing 41 and block 42. In its normal position under the action of the spring 27, the member 13 and block 37 are arranged in a position to 80 dispose the contact pin 40 out of engagement with the arcuate contact plate 46 so that the resistance coil is de-energized.

The device which is especially designed for use on a motor vehicle, has the body 10 90 secured upon the instrument board with the open end uppermost. Cigarettes, cigars, or the like, are arranged in stacked relation in the body and with the parts in a normal position, and it is obvious that the lowermost cigarette will be gravitationally fed through the cutaway portion or opening 17 into the member 13. As heretofore explained, the suction tube 34 is connected with the vacuum tank or any other suction-creating part of the vehicle while the conductor wires 44 and 46 are operatively connected with the storage battery of the same.

When the driver or other occupant of the vehicle desires a cigarette, the handle 26 is 105 turned forward, then downward and pushed inward against the action of the spring 27 to the limit of its movement. This operation turns the member 13 so that the cutaway portion is disposed downward and the 110 remainder of the medial portion of the member 13 disposed upward so as to isolate the lowermost cigarette which has previously gravitated thereinto. At the same time, the inward movement of the handle effects an 115 inner sliding movement of the sleeve 20 against the right end of the isolated cigarette, forcing its opposite end into engagement with the resistance coil 38. This operation further brings the ports 35 and 36 120 into register with each other and into alignment with the opening 32 so that communication is established between the suction tube 34 and the interior of the sleeve 20. At the 125 same time, the contact pin 40 is disposed into contact with the arcuate contact plate 47 to energize the resistance coil for heating the same, whereby the left end of the cigarette is ignited, due to the suction created through the cigarette from its opposite end. The 130

operator then releases the handle 26 and by exerting a pressure on the lip or lug 48 of the closure 11, opens the closure allowing the lighted cigarette to be removed for smoking.

5 Immediately upon release of the handle 26, the spring 27 will function to turn the handle, the sleeve and the member 13 in a reverse direction, thereby returning said parts to their normal position for cutting off 10 the suction, and, at the same time, disengaging the contact pin 40 from the contact plate 47 to de-energize the resistance coil 38. This returns the cutaway portion 17 of the member 13 to the normal upwardly disposed position 15 for gravitationally receiving the succeeding lowermost cigarette C of the stack.

From the foregoing it will thus be seen that a dispensing and lighting container for cigarettes, cigars or the like, has been devised, which is comparatively simple in its construction and mode of operation, thereby eliminating the danger incident to the driver of a vehicle lighting a cigarette or cigar while the vehicle is in motion.

25 What is claimed is:

1. A cigarette dispensing and lighting container including a body adapted to contain a supply of stacked cigarettes, rotatory means at the lower end of said body having 30 a chamber for gravitationally receiving and isolating the lowermost cigarette, said chamber being coaxial with the axis of rotation of said rotatory means, and means operated by and coaxial with said rotatory means 35 for simultaneously creating a suction through the cigarette through one end and for igniting the opposite end.

2. A cigarette dispensing and lighting container including a body adapted to contain a supply of stacked cigarettes, rotatory means at the lower end of said body for 40 gravitationally receiving and isolating the lowermost cigarette, and means operated by and coaxial with said rotatory means 45 for simultaneously creating a suction through the cigarette through one end and for igniting the opposite end, said isolating means consisting of an oscillatory member journaled at the lower end of the body 50 and said suction-creating means, consisting of a valved conduit and a switch-controlled electric heating element coaxial with and 55 operable by turning movement of the isolating means.

3. A cigarette dispensing and lighting container, comprising a body adapted to contain a stacked supply of cigarettes, a rotary cylindrical member journaled transversely in the lower end of the body and 60 having a central semicircular cutaway portion through which the lowermost cigarette of the stack gravitates into the member to a position substantially coaxial therewith, whereby upon turning movement thereof the cigarette thus received is isolated from the

stack, an electric heating element at one end of the member to a position substantially coaxial therewith, switch members adapted to energize said element upon turning movement of the member to a position to isolate 70 a cigarette, and a casing into which the opposite end of the cylindrical member extends, said end of the member and casing each having a suction port adapted to be disposed in registry upon turning movement 75 of the member to the position for isolating a cigarette, whereby suction through the cigarette is effected for the lighting of the opposite end in contact with the electric heating element.

4. A cigarette dispensing and lighting container, comprising a body adapted to contain a stacked supply of cigarettes, a rotary cylindrical member journaled transversely in the lower end of the body and having a central semicircular cutaway portion through which the lowermost cigarette of the stack gravitates into the member to a position substantially coaxial therewith whereby upon turning movement thereof the cigarette thus received is isolated from the stack, an electric heating element at one end of the member in alignment with the cigarette contained therein, switch members operable to energize said element upon turning movement of the member to a position to isolate a cigarette, a casing into which the opposite end of the cylindrical member extends, said end of the member and casing each having a suction port adapted to be disposed in registry upon turning movement 90 of the member to the position for isolating a cigarette, whereby suction through the cigarette is effected for the lighting of the opposite end in contact with the electric heating element, means connected with the cylindrical member for manually rotating the same in the direction to isolate and light the cigarette, and means 95 for returning and normally holding said member in its inactive position with the suction cut off and the heating element de-energized.

5. A cigarette dispensing and lighting container, comprising a body adapted to contain a stacked supply of cigarettes, a rotary cylindrical member journaled transversely in the lower end of the body and having a central semi-circular cutaway portion through which the lowermost cigarette of the stack gravitates into the member to a position substantially coaxial therewith, whereby upon turning movement thereof the cigarette thus received is isolated from the stack, an electric heating element at one end 110 of the member in alignment with the cigarette contained therein, switch members operable to energize said element upon turning movement of the member to a position to isolate a cigarette, a casing into which the

opposite end of the cylindrical member extends, said end of the member and casing each having a suction port adapted to be disposed in registry upon turning movement of the member to the position for isolating a cigarette, whereby suction through the cigarette is effected for the lighting of the opposite end in contact with the electric heating element, means connected with the cylindrical member for manually rotating the same in the direction to isolate and light the cigarette, means for returning and normally holding said member in its inactive position with the suction cut off and the heating element de-energized, and means coaxial with and arranged within the ported end of the member for relative axial sliding movement and connected with the manual rotating means for engaging one end of the cigarette and advancing the opposite end into contact with the heating element.

6. A cigarette dispensing and lighting container, comprising a body adapted to contain a stacked supply of cigarettes, a rotary cylindrical member journaled transversely in the lower end of the body and having a central semi-circular cutaway portion through which the lowermost cigarette of the stack gravitates into the member to a position substantially coaxial therewith, whereby upon turning movement thereof the cigarette thus received is isolated from the stack, an electric heating element at one end of the member in alignment with the cigarette contained therein, switch members adapted to energize said element upon turning movement of the member to a position to isolate a cigarette, a casing into which the opposite end of the cylindrical member extends, said end of the member and casing each having a suction port adapted to be disposed in registry upon turning movement of the member to the position for isolating a cigarette, whereby suction through the cigarette is effected for the lighting of the opposite end in contact with the electric heating element, means connected with the cylindrical member for manually rotating the same in the direction to isolate and light the cigarette, means for returning and normally holding said member in its inactive position with the suction cut off and the heating element de-energized, and means coaxial with and arranged within the ported end of the member for relative axial sliding movement and connected with the manual rotating means for engaging one end of the cigarette and advancing the opposite end into contact with the heating element, said latter means being normally moved outwardly and having a suction-receiving port registerable with the port in the cylindrical member upon inward sliding movement.

7. In a device of the class described, the combination with an open end magazine

adapted to receive a supply of cigarettes, of a tubular member rotatably mounted at the open end of said magazine closing the same, said member having a cut away portion adapted to register with the open end of said magazine, through which one of the cigarettes contained in said magazine may be fed into said tubular member, for the purpose of isolating it from the other cigarettes upon rotation of said tubular member, and means coaxial with said tubular member for simultaneously creating a suction through one end of the cigarette contained therein and for igniting the opposite end.

8. In a device of the class described, the combination with an open end magazine adapted to receive a supply of cigarettes, of a tubular member rotatably mounted at the open end of said magazine closing the same, said member having a cut away portion adapted to register with the open end of said magazine, through which one of the cigarettes contained in said magazine may be fed into said tubular member, for the purpose of isolating it from the other cigarettes upon rotation of said tubular member, means coaxial with said tubular member for creating a suction through one end of the cigarette contained therein and means for igniting the opposite end when said tubular member is moved from its receiving to its isolating position.

9. In a device of the class described, the combination with an open end magazine adapted to contain a supply of cigarettes, and a dispensing member provided with a cigarette receiving chamber at said open end adapted to receive and isolate one of the cigarettes contained in said magazine, of an igniting element carried by said member and mounted at one end of said chamber, adapted to be placed in commission by the isolating operation of said member.

10. In a device of the class described, the combination with an open end magazine adapted to contain a supply of cigarettes, of a tubular member rotatably mounted at the open end thereof, said member having a cut away portion through which one of the cigarettes contained in said magazine may be fed into said tubular member, an igniting device at one end of said tubular member adapted to be placed in commission when said member is rotated from one position to another, and a suction member coaxial with and axially movable in relation to said tubular member adapted to force the cigarette contained therein against the igniting device.

11. In a device of the class described, the combination with a magazine adapted to contain a supply of cigarettes and means associated therewith for receiving and isolating one of the cigarettes contained therein,

of means for igniting said cigarette while said receiving and isolating means is moving from the receiving of the isolating position.

12. In a device of the class described, the combination with an open end magazine adapted to contain a supply of cigarettes, of a dispensing member rotatably mounted at the open end thereof, said member comprising an open side tubular shell adapted to receive one of the cigarettes contained in said magazine and adapted to isolate the same from the others by becoming interposed between said cigarette and the remaining cigarettes in the magazine upon said dispensing member being rotated about its own axis, and means associated with said dispensing member for lighting the cigarette isolated thereby, while said dispensing member being moved from one of its extreme positions to the other.

13. In a device of the class described, the combination with an open end magazine adapted to contain a supply of cigarettes, of a dispensing member rotatably mounted at the open end thereof, said member comprising an open side tubular shell adapted to receive one of the cigarettes contained in said magazine and adapted to isolate the same from the others by becoming interposed between said cigarette and the remaining cigarettes in the magazine upon said dispensing member being rotated about its own axis, an igniting element mounted at one end of said dispensing member, a suction member coaxial with said dispensing member slidably mounted within the same at the other end, means causing said igniting element to become energized when the dispensing member is brought to its dispensing position, and means for axially shifting and for rotating said suction member about its axis, forcing the cigarette within the dispensing member against the igniting element and causing rotatory movement of said dispensing member from its receiving to its dispensing position.

14. In a device of the class described, the combination with an open end magazine adapted to contain a supply of cigarettes, of a dispensing member rotatably mounted at the open end thereof, said member comprising an open side tubular shell adapted to receive one of the cigarettes contained in said magazine and adapted to isolate the same from the others by becoming interposed between said cigarette and the remaining cigarettes in the magazine upon said dispensing member being rotated about its own axis, and an igniting element at one end of said dispensing member, coaxial therewith adapted to become energized when said dispensing member is moved from its receiving to its isolating position.

15. In a device of the class described, the combination with an open end magazine

adapted to contain a supply of cigarettes, of a dispensing member rotatably mounted at the open end thereof, said member comprising an open side tubular shell adapted to receive one of the cigarettes contained in said magazine and adapted to isolate the same from the others by becoming interposed between said cigarette and the remaining cigarettes in the magazine upon said dispensing member being rotated about its own axis, an igniting element at one end of said dispensing member adapted to become energized when said dispensing member is moved from its receiving to its isolating position, and an axially movable suction member registering with said tubular shell, adapted to force the cigarette contained therein against said igniting element.

16. In a device of the class described, the combination with an open end magazine adapted to contain a supply of cigarettes, and a dispensing member rotatably mounted at said open end, said dispensing member having a cigarette receiving chamber coaxial therewith, of a suction member coaxial with said dispensing member and chamber, adapted to be axially displaced in relation to said chamber.

17. In a device of the class described, the combination with an open end magazine adapted to contain a supply of cigarettes, of a dispensing member rotatably mounted at the open end thereof, said member comprising an open side tubular shell adapted to receive one of the cigarettes contained in said magazine and adapted to isolate the same from the others by becoming interposed between said cigarette and the remaining cigarettes in the magazine upon said dispensing member being rotated about its own axis, and an igniting element at one end of said dispensing member adapted to become energized when said dispensing member is moved from its receiving to its dispensing position, and means coaxial with said dispensing member adapted to create a draft through the cigarette being lighted by said igniting element.

18. In a device of the class described, the combination with a magazine adapted to contain a supply of cigarettes and a dispensing member having a chamber adapted to receive one of the cigarettes contained in said magazine, said dispensing member being movable from the receiving to a dispensing position, of an igniting element coaxial with said chamber, adjacent one end thereof and means associated with said dispensing member, for energizing said element during the period of travel of said dispensing member at a point intermediate of its two extreme positions.

19. A cigarette lighter and dispenser comprising a casing, a magazine mounted in said casing for supporting a plurality of ciga-

- rettes therein, a suction mechanism adapted to engage one end of said cigarette, a lighting mechanism adapted to engage the other end of said cigarette, supporting mechanism 5 for positioning and discharging said cigarette and means operatively connected with said supporting mechanism and actuated by a single manipulation thereof, for operating in connection with said mechanisms for 10 igniting and discharging said cigarette.
20. A cigarette lighter and dispensing device comprising a casing, means for supporting a plurality of cigarettes therein, a shaft oscillatably mounted in said casing, 15 supporting and discharging means mounted on said shaft for supporting and discharging one cigarette at a time, a suction means including a valve mounted on said shaft and having a connection thereon adapted to engage 20 one end of said cigarette, a heating element mounted on said shaft and adapted to engage the other end of said cigarette and single means for manipulating said shaft and heating element to bring the opposite 25 ends of said cigarette in contact with said suction means and said heating element and to oscillate said shaft to discharge said cigarette in lighted condition. 80
21. In a dispensing machine, a magazine 30 for containing articles to be dispensed, an article receiver having a lighting position, a lighter operating at said position, a supply position on one side of the lighting position, a delivery position on the other side of the lighting position, and a suction device for the article operating thereon at 85 said lighting position. 90
22. A cigarette dispensing and lighting container including a body adapted to contain 40 a supply of stacked cigarettes, rotatory means at the lower end of said body for gravitationally receiving and isolating the lower-most cigarette, and means operated by and coaxial with said rotatory means for 45 simultaneously creating a suction through the cigarette through one end and for igniting the opposite end, said isolating means consisting of an oscillatable member journaled at the lower end of the body and said suction-creating means, consisting of a valved conduit and a switch-controlled electric heating element coaxial with and operable by turning movement of the isolating 50 means. 100
23. A holder and igniter for cigarettes and the like comprising a receptacle, a rotary cylinder closing the bottom of the receptacle and having a longitudinal groove in its periphery, igniting means, a contact 55 therefor movable with said cylinder and normally displaced from said igniting means, and arranged to be brought into circuit closing relation therewith by a partial delivery turn of said cylinder. 110
24. A holder and igniting means for cigarettes 60 and the like comprising a receptacle, a rotary cylinder closing the bottom of the receptacle and having a longitudinal slot in its periphery, a circuit closing contact for said igniting means movable with said cylinder and normally disengaged with respect to said igniting means, and an operating handle for turning said cylinder to isolate a cigarette therein, and for simultaneously moving said contact therewith to 75 close the circuit of said igniting means. 120
- AUGUST KÄPPENBERG. 130
